US00D799519S

(12) **United States Design Patent** (10) **Patent No.:** **US D799,519 S**
(45) **Date of Patent:** **** Oct. 10, 2017**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Lee Broughton**, Santa Cruz, CA (US); **Kevin Will Chen**, Sunnyvale, CA (US); **Nathan De Vries**, San Francisco, CA (US); **Alan C. Dye**, San Francisco, CA (US); **Christopher Foss**, San Francisco, CA (US); **Jonathan P. Ive**, San Francisco, CA (US); **Christopher Wilson**, San Francisco, CA (US)

(73) Assignee: **Apple Inc.**, Cupertino, CA (US)

(**) Term: **15 Years**

(21) Appl. No.: **29/567,726**

(22) Filed: **Jun. 22, 2016**

(51) **LOC (10) Cl.** **14-04**

(52) **U.S. Cl.** **D14/486**
USPC **D14/486**

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
